DESIGN FOR A FRUIT JUICE EXTRACTOR

Joseph M. Majewski, Jr., Kansas City, Mo., assignor to Foster L. Talge, doing business as Rival Manufacturing Company, Kansas City, Mo.

Application June 8, 1936, Serial No. 63,091

Term of patent 7 years

To all whom it may concern:

Be it known that I, Joseph M. Majewski, Jr., residing at Kansas City, in the county of Jackson and State of Missouri, have invented a new, original, and ornamental Design for a Fruit Juice Extractor, of which the following is a specification, reference being had to the accompanying drawing forming part thereof, in which—

I claim:

The ornamental design for a fruit juice extractor, substantially as shown.

In testimony whereof, I affix my signature.

JOSEPH M. MAJEWSKI, JR.
